US0D1015348S

(12) **United States Design Patent** (10) Patent No.: **US D1,015,348 S**
 Clarke et al. (45) Date of Patent: ** Feb. 20, 2024

(54) **DISPLAY SCREEN OR PORTION THEREOF WITH GRAPHICAL USER INTERFACE**

(71) Applicant: **Foundry Innovation and Research 1, Ltd.**, Dublin (IE)

(72) Inventors: **Natasha Clarke**, Dublin (IE); **John Britton**, Dublin (IE); **Friedrich Wetterling**, Dublin (IE); **Michael Kelly**, Dublin (IE); **Fiachra Sweeney**, Dublin (IE)

(73) Assignee: **Foundry Innovation & Research 1, Ltd.**, Dublin (IE)

(**) Term: **15 Years**

(21) Appl. No.: **29/831,457**

(22) Filed: **Mar. 21, 2022**

Related U.S. Application Data

(63) Continuation of application No. 29/733,075, filed on Apr. 29, 2020, now Pat. No. Des. 946,622.

CLAIM

The ornamental design for a display screen or portion thereof with graphical user interface, as shown and described.

DESCRIPTION

The sole FIGURE is a front view of a display screen or portion thereof with graphical user interface, showing our new design.

The peripheral broken lines in the FIGURE shows a display screen or portion thereof, and forms no part of the claimed design. The broken lines within the peripheral broken lines show portions of the graphical user interface and form no part of the claimed design.

1 Claim, 1 Drawing Sheet
